UNITED STATES PATENT OFFICE.

WILLIAM HARROP, PETER REILLY, AND PATRICK F. FARRELL, OF NEW BEDFORD,
MASSACHUSETTS.

SPLIT-LAP PREVENTER.

Application filed March 25, 1922. Serial No. 546,783.

To all whom it may concern:

Be it known that we, WILLIAM HARROP, PETER REILLY, and PATRICK F. FARRELL, citizens of the United States, residing at 5 New Bedford, in the county of Bristol and State of Massachusetts, have invented certain new and useful Improvements in Split-Lap Preventers, of which the following is a specification, reference being had to the accompanying drawings.

This invention relates to cotton yarn forming machinery, and particularly to sliver lap machines or to machines of like character, such as pickers, ribbon lappers, 15 etc.

In the operation of machines of the character described, and where a sliver lap or thin layer of carded or partially combed cotton is wrapped spirally upon a receiving roll, there is a liability of the material in one layer becoming tangled with the material of the other layer and as a consequence the lap will not unroll evenly, as it should, but the lap "splits" and thus the 20 material is not fed in the subsequently operating machine evenly.

The general object of our invention is to prevent this by disposing a separating thread between the layers of sliver as they 30 are wrapped upon the receiving roll or spool.

A further object is to provide an attachment for sliver lap machines, pickers, ribbon lappers, etc., whereby this separating thread may be laid upon the upper surface 35 of the sliver as it passes between the calender rolls, and furthermore whereby this thread may be laid in a zigzag course across the upper face of the sliver.

40 Still another object is to provide means whereby the usual stop motion of the sliver lap or equivalent means may be caused to be actuated upon the breaking of the thread.

Another object is to so construct the attachment that the thread may be fed to the 45 machine between the sliver lap and the upper calender rolls with a sufficient tension and may be fed at a speed corresponding to the speed of the lap.

50 Other objects have to do with the details of construction and arrangement of parts as will appear more fully hereinafter.

Our invention is illustrated in the accompanying drawings, wherein:—

Figure 1 is a fragmentary side elevation 55 of a portion of a sliver lap machine showing our invention applied in connection with the calender rolls thereof;

Figure 2 is a front elevation of the calender rolls and our mechanism applied 60 thereto;

Figure 3 is a longitudinal sectional view through the housing enclosing the worm;

Figure 4 is a face view of the lap after 65 the thread Y has been applied thereto.

In Figure 1, we illustrate sufficient of a sliver lap machine of ordinary construction to show the application of our invention, and in these drawings A—A indicate an upper pair of calender rolls, B—B the 70 lower pair of calender rolls, C the draft rolls, D the spool upon which the lap is being wound or wrapped, and E—E the usual fluted lap rolls which support the wooden spool E. All the parts are of any suitable 75 or usual construction, it being understood that the sliver passes from the usual cans through guides (not shown) to the draft rolls C and thence between the calender rolls A and B, and from thence to the winding spool D. The sliver passing between the calender rolls is designated X.

Our attachment comprises supports 10 which are attached to the frame of the sliver lap machine and extend upward therefrom slightly in advance of the series of calender rolls. This frame supports upon it a shaft 11 carrying a pulley 12 and rotated by a rope drive 13 from the main shaft of the machine, this shaft 11 carrying upon it a reversely screw-threaded worm or equivalent member 14 having a continuous screw-thread. Operatively engaged by this worm and, therefore, traveling back and forth across the machine is a traveler 15. This 95 traveler has an arm 16 projecting outward therefrom, which carries an ordinary trumpet 17 at its forward end. The upper ends of the brackets or supports 10 carry a transverse rod 18.

The thread which is to separate the two adjacent layers of sliver is wound upon a roll 19, the periphery of the roll of thread resting upon the upper calender rolls A.

Inasmuch as these calender rolls rotate in a counter-clockwise direction, it will be obvious that the roll 19 will rotate in a clockwise direction and that as the machine operates the thread will be drawn off the roll 19 down through the trumpet 17. This thread passes beneath the upper calender rolls A and rests upon the upper face of the sliver lap X which is passing between the 10 rolls. The traveler 15 has a traverse equal in width to the width of the lap or sliver and as a consequence the thread will be laid in a zigzag fashion upon the upper face of the sliver, as illustrated in Figure 4, and 15 this thread will thus be disposed between the layers of sliver on the lap spool B, separating these layers and preventing them from becoming entangled. It will be seen that the thread is drawn in between the rolls 20 A and the lap at a speed equal to that of the lap, and that there is only a slight tension on this thread because of the fact that the roll 19 is positively rotated by the calender rolls.

25 Every sliver lap machine or ribbon lapper is provided with an electrical stop motion whereby in case the lap becomes thin or breaks, the machine will be immediately brought to a stop by the closing of a circuit 30 through the metallic parts of the machine, this circuit being normally held open by the interposition of the lap between certain metallic parts. In order to provide means for stopping the machine in case the separating 35 thread Y breaks, we mount upon the travel 15 the angular lever 20. This lever is pivotally mounted upon the traveler and its longer arm extends downward and rearward toward the first upper calender roll A, while 40 the shorter arm of the lever extends downward and forward and is formed with an elongated eye 21, beneath which the thread Y passes. This elongated eye 21 is so disposed that the thread in its passage 45 from the trumpet to the calender roll will frictionally engage this eye and tend to draw it downward, thus lifting the rear arm 22 off of the calender roll. If, for any reason, the thread Y should break and, 50 therefore, the tension of the thread between the trumpet 17 and the calender roll be relaxed, the eye 21 will move upward and the arm 22 will move downward and into electrical engagement with the calender roll. 55 This will energize an electro-magnet, which in turn will act to draw a suitable stop into position in front of an arm on the rock shaft of the machine and thus stop the operation of the machine in a manner well 60 known to those who are skilled in the art.

Inasmuch as this mechanism which we have described is simply a means for closing a circuit and thereby stopping the machine by the ordinary stop mechanism common 65 to these machines, we have not indicated the

ordinary stop mechanism but have illustrated diagrammatically in Figure 1 the lever 20 and the calender roll A as being connected in a normally open circuit by electric conductors 23 and 24. The conductor 23 leads 70 to one pole of the battery 25 and an electro-magnet 26 is disposed between the wire 24 and the battery 25. A pivoted stop 27 constitutes the armature of the electro-magnet 26 and when this pivoted stop is raised 75 by energizing the magnet 26, it is lifted into position in front of an arm 28 on a rock shaft 29, this rock shaft being found on all machines and being used for the purpose of stopping the machine in the well known 80 manner.

We have illustrated diagrammatically the lever 20 and the forward calender roll A as being electrically connected by wires directly to the battery 25, but it will be understood that these wires 23 and 24 are merely symbolic of any conductive circuit and the circuit might be made through any metallic parts of the machine, and the circuit may be either grounded at one end or have a return conductor.

While we do not wish to be limited to the particular arrangement of the worm 14, we have illustrated in Figure 3 a preferable construction wherein the worm 14 is disposed within a housing 30, the traveler 15 sliding upon this housing and this traveler carrying an inwardly extending pin 31 formed with a head 32 engaging in the screw-thread in the worm 14. As the worm rotates continuously in one direction, it will be obvious that the traveler will slide back and forth in the manner heretofore stated, the traveler being guided in the slot 33 of the housing through which the pin 31 projects.

The operation of the mechanism is obvious from what has gone before, and it will be seen that by the means which we have described a thread is laid down in a zigzag path between the layers of lap as they are rolled up upon the receiving roll so that the layers are to this extent separated and there is no possible chance for any splitting of the lap. We do not wish to be limited to the particular form of traverse mechanism shown for causing the traverse of the traveler 15, but this traverse mechanism is simple, positive and thoroughly effective for the purpose. Other details might be modified in many ways without departing from the spirit of the invention as defined in the appended claims.

We claim:

1. In a machine of the character described, 125 the combination with a winding spool upon which the lap is wound, of means for disposing a separating thread in an approximately zigzag line upon the face of the lap prior to its passage to the winding spool.

2. The combination with a sliver lap machine including rolls between which the lap passes, and a winding spool upon which the lap is wound, of means for disposing a separating thread in a zigzag line upon the face of the lap prior to its passage to the winding spool. 55
3. A sliver lap machine including calendering rolls, a winding spool, and means for disposing a separating thread upon the lap prior to its passage to the calendering rolls, and in a zigzag course over the face of said lap. 60
4. A sliver lap machine including calendering rolls, a winding spool, and means for disposing a thread in a zigzag course upon the face of the lap prior to its passage through the calendering rolls and including a traveler having a thread guide, and means 65
- 20 acting to cause the traverse of said traveler alternately in opposite directions transverse to the path of movement of the lap.
5. A sliver lap machine including calendering rolls, a winding spool, and means for disposing a thread in a zigzag course upon the face of the lap prior to its passage through the calendering rolls and including a traveler having a thread guide, means 70
- 30 acting to cause the traverse of said traveler alternately in opposite directions transverse to the path of movement of the lap including an endless reverse screw with which the traveler engages, and means connected to the driving mechanism of the machine for 75
- 55 rotating said screw.
6. A sliver lap machine including calendering rolls, a winding spool, and means for disposing a thread in a zigzag course upon the face of the lap prior to its passage 80
- 40 through the calendering rolls and including a traveler having a thread guide, means acting to cause the traverse of said traveler alternately in opposite directions transverse to the path of movement of the lap, and a 85
- 45 thread containing spool resting upon the upper calendering rolls, the thread passing to and through the guide carried by the traveler.
7. In a sliver lap machine, upper and 90
- 50 lower pairs of calendering rolls, a lap receiving spool, and means for laying a thread in a zigzag course upon the face of the lap prior to its passage through the calendering rolls comprising a thread spool, a thread
- guide, a traveler having a trumpet, and means for giving a reciprocation to the traveler transverse to the path of movement of the lap, the thread from said spool passing over the first named guide and to said trumpet and thence between the calendering 95
- rolls.
8. A method of preventing split laps consisting in laying between the laps a thread having portions extending transversely of the lap. 65
9. A method of preventing split laps consisting in disposing a thread in a zigzag course between the contacting faces of adjacent laps. 70
10. A sliver lapping machine including a receiving spool upon which the lap is wound, means for laying a thread in a zigzag course upon the face of the lap prior to its being wrapped upon the receiving spool, and means for stopping the sliver lapper in case 75
- said thread breaks.
11. A sliver lapping machine including a receiving spool upon which the lap is wound, means for laying a thread in a zigzag course upon the face of the lap prior to its being wrapped upon the receiving spool, means 80
- 85 for stopping the sliver lapper in case said thread breaks including an electrically actuated stopping mechanism, and contacts adapted to close a circuit through the stopping mechanism, said contact being normally held in an open circuit position by the passage of the thread. 85
12. A sliver lapping machine including a receiving spool upon which the lap is wound, means for laying a thread in a zigzag course upon the face of the lap prior to its being wrapped upon the receiving spool, means for stopping the sliver lapper in case said thread 90
- 95 breaks including an electrically operated stopping mechanism normally in an open circuit with a source of current, and a lever adapted to close said circuit and having an eye frictionally engaged by the thread when the thread is under tension, the engagement 100
- of the thread with the lever holding the lever in an open circuit position. 100

In testimony whereof we hereunto affix our signatures.
